DOCTORING MEANS FOR GLUING ROLLERS

Robert Minkow, New York, N. Y.

Application October 6, 1948, Serial No. 53,107

2 Claims. (Cl. 118—261)

1

This invention relates to gluing machines and is an improvement over the structure embodied in my copending application Serial Number 2,270, filed January 14, 1948, for Gluing Machine, now Patent No. 2,554,587.

An object of this invention is to provide a gluing machine which is so constructed that the tapes of interengageable fasteners may be coated with glue or suitable adhesive, and at the same time other articles may be run through the machine.

Another object of this invention is to provide in a gluing machine an adjustable scraping bar for the gluing roller so that the desired depth of glue on the gluing roller may be maintained, the bar also including a scraping finger for removing all of the glue in alignment with the metal fasteners so that the latter will not stick together.

A further object of this invention is to provide a gluing machine of this kind, including a pair of adjustable tape guides mounted on the table for guiding the articles in a straight line to the gluing roller.

With the above and other objects in view, my invention consists in the arrangement, combination and details of construction disclosed in the drawings and specification, and then more particularly shown in the appended claims.

In the drawings:

Figure 1 is a plan view, partly broken away, of a gluing machine constructed according to an embodiment of this invention.

Figure 2 is a fragmentary sectional view taken on the line 2—2 of Figure 1.

Figure 3 is a fragmentary sectional view taken on the line 3—3 of Figure 2.

Referring to the drawings, the numeral 10 designates generally a frame or body structure constructed in the form of an upwardly opening receptacle or well within which glue is adapted to be positioned. The frame 10 has rotatably mounted therein a gluing roller 11 which is formed with a peripheral groove or channel 12 between the ends thereof, and preferably adjacent one end.

The frame 10 has rotatably mounted therein a pair of pressure rollers 13 and 14, disposed above the gluing roller 11 and adapted to press the articles which are glued on one face thereof downwardly against the gluing roller 11. The frame 10 also includes a horizontally disposed table 15 over which the articles to be glued are moved, and on the delivery side of the pressure rollers 13 and 14 a plurality of pick-off fingers 16 are rockably mounted on a transverse guide and supporting bar 17. The pick-off fingers 16 may be ad-

2

justed lengthwise of the bar 17 and are adapted to contact with the surface of the gluing roller 11.

The table 15 has mounted on the upper side thereof a pair of lengthwise extending spaced apart angle-shaped guide members 18 and 19, which have their inner sides 20 and 21 vertically disposed and resting on the upper surface of the table 15. The horizontal sides 22 and 23 of the angle members 18 and 19 are formed with transversely extending elongated openings 24 and 25 through which bolts 26 and 27 respectively are extended so that the guide members 18 and 19 may be adjusted toward or away from each other so that an interengageable fastening element 28 may slidably engage between the vertical sides 20 and 21.

The guide members 18 and 19 are mounted in a position whereby the metal locking elements 29 of the fastening means 28 will ride over the groove or channel 12 and the pressure rollers 13 and 14 are also formed with peripheral grooves or channels 30 and 31 respectively, adapted to overlie the groove 12. In this manner when the fastening means 28 is passing through the machine, the metal elements 29 will not be placed under any pressure.

The gluing roller 12 has associated therewith a glue removing bar 32 which extends transversely across the frame 10 and the bar 32 is carried by a supporting bar 33. The supporting bar 33 is slidably mounted on guide means 34 carried by the frame 10, and the supporting bar 33 is constantly urged forwardly toward the gluing roller 11 by means of a tensionable spring 35. The spring 35 engages about a rearwardly extending rod 36 which is fixed at its forward end to the supporting bar 33 and extends through a guide 37 carried by the frame 10.

A washer or collar 38 is fixed on the rod 36 rearwardly of the guide 37 and a second collar 39 is slidable on the rod 36 and bears at its rear end against a rear guide 40 which is carried by the frame 10. A spring tensioning nut 41 is threaded on the rear portion of the rod 36 and a lock nut 42 is also threaded on the rod 36 and bears against the nut 41. The glue which enters the channel 12 at the lower portion of the gluing roller 11 is substantially entirely removed therefrom by means of a scraping finger 43 which is adjustably carried by the bar 33. The scraping finger 43 is formed at its rear end with a downwardly and right angularly disposed arm 44 through which a finger adjusting bolt 45 is rotatably mounted. The bolt 45 is threaded into the

bar 33 and the bolt 45 has fixed thereto a pair of collars 46 and 47 disposed on opposite sides of the arm 44. A knob 48 is fixed to the rear end of the bolt 45 so that this bolt may be rotatably adjusted to move the scraping finger 43 toward or away from the groove 12.

In the use and operation of this machine, the guide members 18 and 19 are adjusted toward or away from each other so that the fastening means 28 may freely slide therebetween. The scraping bar 32 is adjusted toward or away from the gluing roller 11 so that the desired film of glue will be retained on the gluing roller for contact with the lower side of the tapes carried by the fastening means 28. When the scraping bar 32 has been properly adjusted, the scraping finger 43 may be moved forwardly into the groove or channel 12 so as to remove substantially all of the glue from this groove or channel in order that the metal elements 29 will not be contacted by the glue. At the same time that a fastening means 28 is being moved through the gluing machine, other flat articles which are to be glued on one face thereof may also be passed through the machine. In this manner the gluing machine may be used for specifically gluing the tapes of a fastening means such as an interengageable fastening means and may also be used for gluing other flat articles of leather, plastic, fabric, cardboard or other material.

As shown in Figure 1, at least one of the lifting members 16 is formed with a pair of lifting fingers 49 which engage in the groove 12 and a pair of lifting members 16 are disposed one on each side of the lifting member 16a so that the fabric tape of the fastening means 28 will be removed from the gluing roller on the discharge or delivery side of the machine.

I do not mean to confine myself to the exact details of construction herein disclosed, but claim all variations falling within the purview of the appended claims.

What I claim is:

1. A gluing machine comprising a frame, a gluing roller rotatably carried by said frame, an annular groove formed in said roller, a glue removing device disposed transversely of said frame including a pair of parallel guide means extending at right angles to the axis of said roller, a

scraper bar slidably carried by said guide means for movement in a direction parallel to said guide means, spring means constantly urging said bar towards said roller, adjustable stop means connected to said bar limiting the movement of said bar towards said roller, a scraping finger slidably carried by said bar and engageable in said annular groove, and means carried by said bar and engaging said scraping finger for adjustably positioning the latter relative to said bar.

2. A gluing machine comprising a frame, a gluing roller rotatably carried by said frame, and a glue removing device disposed transversely of said frame including guide means extending at right angles to the axis of said roller, a scraper bar disposed parallel to said roller axis slidably carried by said guide means for movement towards and away from the surface of the roller, bearing members carried by said frame in alignment with said guide means, elongated rods fixed at one end to said scraper bar and slidably extending through said bearing members, spring means fixed at one end to said rods and at the other end to said bearing members constantly urging said rods and said scraper bar towards said roller, the other ends of said rods being threaded, and adjusting nuts threaded on said other ends of said rods and abutting against said bearing members limiting the movement of said rods and said scraper bar towards said roller to thereby control the thickness of the glue film on said roller, and a forwardly extending finger member carried by said bar having an end engageable with said roller at a point disposed from the forward edge of said scraper bar.
